UNITED STATES PATENT OFFICE.

LUTTRELL H. STUART, OF CHICAGO, ILLINOIS.

VALVE.

Application filed August 28, 1926. Serial No. 132,244.

This invention relates to valves especially adapted for use on internal combustion engines, although not necessarily restricted to such use.

5 Briefly stated, an important object of this invention is to provide novel means whereby the intake and exhaust of an engine cylinder is reliably controlled by a slide valve mechanism in which the opening and closing of the 10 ports is regulated by a cam or eccentric operating from or off the crank shaft or a special cam shaft.

Other objects and advantages will be apparent during the course of the following 15 description.

In the accompanying drawings forming a part of this application and in which like numerals are employed to designate like parts throughout the same,

20 Figure 1 is a vertical section through the valve mechanism applied, omitting a valve operating lever;

Figure 2 is a side elevation of the improved 25 valve mechanism applied, parts being in section;

Figure 3 is a group perspective of the valve;

Figures 4 to 7, inclusive, are diagrams illustrating the cycle of operation.

In the drawing, the numeral 5 designates a 30 cylinder within which the usual piston operates, and, of course, the piston has connection with a crank shaft through the medium of a connecting rod, all of which is old and well known.

35 In carrying out the invention one side or other portion of the cylinder is provided with a valve casing 6 within which a vertically slidable valve 7 is mounted. The valve 7 is provided with an intake port 8 and an exhaust port 9, these two ports being at approximately the same points on the slide valve.

The port 8 is adapted to communicate with an intake port 10 in the engine cylinder to permit of the supply of a combustible fuel to the 40 combustion chamber of the engine. It is obvious that a carburetor is connected to the valve casing 6 either directly or through the medium of a manifold and when the port 8 is in registration with the port 10 on the intake stroke of the piston combustible fuel is admitted to the combustion chamber. It will, therefore, be seen that the slide valve 7 is on its down stroke while the piston is partaking of its suction stroke, but the slide valve travels at only one-half the rate of travel of the

piston as will be more fully hereinafter described.

When the valve 7 reaches the limit of its upward movement, the port 9 therein, will register with the exhaust port 11 in the cylinder whereby to allow of the escape of the product of combustion.

60 The slide valve 7 is operated by a rod or stem 14, the lower portion of which has connection with a crank 15 through the medium 65 of a link 16, this feature of the invention being fully illustrated in Figure 1. With reference to this figure, it will be seen that the crank 15 is operated at one half engine speed by reason of the ratio of the timing gears so 70 that on the initial turning of the main crank shaft in a clockwise direction the ports 8 and 10 will be brought into registration for admitting a charge of combustible fuel. However, the continued downward movement of 75 the slide valve 7 will cause the port 8 to move out of registration with the port 10, and it is important to note that the piston partakes of its compression stroke or at least a substantial part of it before the crank 15 has turned 80 180 degrees. Therefore, the intake port will remain closed during the entire compression stroke as is obviously necessary. In other words, the slide valve reaches the limit of its descent while the piston is on its compression stroke and the slide valve starts its upward travel while the piston is still on its compression stroke, during which time all valves are closed.

85 Further upward movement of the valve is caused by the continued turning of 85 the crank 15 and the piston will partake of its power stroke while the valve is moving upwardly.

90 It may be pointed out at this time that during the upward movement of the valve on the power stroke of the piston, the ports 8 and 10 will be brought into registration for a limited period, but no communication is established between the carburetor and the combustion chamber due to a supplemental valve, 95 the structure and operation of which will be described.

100 When the slide valve reaches the limit of its upward movement, subsequent, of course, to the power stroke, the exhaust ports 9 and 11 will be brought into registration to allow of the escape of the products of combustion on the exhaust stroke.

105 The registration of the exhaust ports 9 and 11 completes one cycle of operation of 110

the main valve and the next cycle is started by the descent of the valve and during a portion of this descent the intake ports 8 and 10 are in registration.

5 Coming now to the description of the supplemental valve for controlling the intake on the upward movement of the main valve 7, attention is directed to Figure 2 which illustrates that the supplemental valve 20 moves 10 across the port 8 and has a stem 21 to which a crank or operating lever 22 is pivoted. The crank 22 has its major portion bowed to define what might be said to be a pair of cams 22^a, 22^b at opposite sides of the fulcrum 24.

15 The cams surfaces 22^a, 22^b at opposite sides of the fulcrum 24 are directly in the path of travel and are adapted to be engaged by the pin or actuating member 30 on the stem 14 of the main valve. When the actuating 20 member 30 approaches the limit of its descent on the compression stroke of the piston, it will engage the lower cam portion 22^b of the crank 22 and will thereby move the valve 20 to a closed position so that on the subsequent 25 power stroke, no communication will be established between the carburetor and the combustion chamber. Such communication would, of course, be fatal to the successful operation of the engine.

30 Now, when the actuating member 30 approaches the limit of its upward movement it will engage the upper cam surface 22^a of the crank 22 so that the supplemental valve 20 is moved to its retracted or what might be 35 said to be its opened position. Of course, the movement of the valve 20 to its retracted or opened position is not productive of immediate results, but merely allows of the communication of the carburetor with the 40 combustion chamber when the ports 8 and 10 are subsequently brought into registration on the intake stroke of the piston.

In carrying out the invention suitable 45 packings may be employed for the different valves and of course means may be provided to carry off the products of combustion in case the engine is used in an automobile.

Having thus described the invention, what is claimed is:

50 1. A valve for engines comprising a casing having intake and exhaust ports, a slide valve having intake and exhaust ports arranged side by side and adapted for registration with said first named ports, one of the 55 ports in said casing being in advance of the other, and a supplemental valve controlling the flow of fuel through said intake ports.

2. The combination with a cylinder having 60 intake and exhaust ports, of a valve slideable across said ports and having a stem provided with a lug, and a supplemental valve controlling one of said ports and having an op-

erating lever fulcrumed between the ends thereof and having cam surfaces at opposite sides of the fulcrum, said cam surfaces being 65 in the path of travel of and adapted to be engaged by said lug whereby the operation of said stem actuates said lever and the supplemental valve connected thereto.

3. The combination with a cylinder having 70 intake and exhaust ports, a valve slideable across said ports and provided with intake and exhaust ports adapted for communication with said first named ports, a stem connected to said valve and provided with a lug, 75 a supplemental valve associated with said intake ports and having an operating lever, a portion of which is bowed to define cam surfaces, said cam surfaces being located at 80 opposite sides of said lug and adapted to be engaged thereby to operate said supplemental valve.

4. The combination with a cylinder having 85 intake and exhaust ports, a valve slideable across said ports and provided with intake and exhaust ports adapted for communication with said first named ports, a stem connected to said valve and provided with a lug, 90 a supplemental valve associated with said intake ports and having an operating lever, a portion of which is bowed to define cam surfaces, said cam surfaces being located at 95 opposite sides of said lug and adapted to be engaged thereby to operate said supplemental valve, said lever being fulcrumed between said cam surfaces.

5. A valve for engines comprising a casing having intake and exhaust ports, a slide valve movable to periodically open and close 100 said ports, a second slide valve in said casing and operable transversely of said first valve to cooperate therewith in the control of one of said ports, and said first valve having an operative connection with the second valve.

6. A valve for engines comprising a casing having intake and exhaust ports, a slide valve movable to periodically open and close 105 said ports, a second valve for closing one of said ports at certain times, a closure for said casing and carrying said second valve, and an 110 operative connection between said valves.

7. A valve for engines comprising a casing having intake and exhaust ports, a closure 115 for said casing, a slide valve for controlling said ports, a second slide valve carried by said closure and movable substantially transversely of said first slide valve to cooperate with the same in controlling said ports, cam means associated with said casing and connected to one of said valves, actuating means for the other valve, and cam actuating means carried by the latter valve.

In testimony whereof I affix my signature.
LUTTRELL H. STUART.
